UNITED STATES PATENT OFFICE.

JOHN MATTUS AND WALTER BETCKE, OF DAKOTA CITY, NEBRASKA.

GAS SAVER.

Application filed March 10, 1925. Serial No. 14,541.

This invention relates to an improved automotive appliance frequently referred to as a gas saver, and it has more particular reference to a device of this class which serves 5 to conduct oil and unconsumed fuel from the crank case to the carburetor.

It is of course a well known fact that fuel obtained from this source and introduced into the carburetor serves to save from one- 10 fourth to one-third of the gas.

In carrying out the present invention it has been our primary aim to generally improve upon a device of this class by providing one which is used in association with a 15 transmission cover plate and which is provided with a flexible conduit leading from this cover plate to a hot air supply pipe such as is used in conjunction with a carburetor on a Ford type of automobile.

20 Numerous advantages and features of the specific construction employed will become apparent from the following description and drawing.

In the accompanying drawing forming a 25 part of this application and in which like numerals are employed to designate like throughout the same:

Figure 1 is a side elevation of a portion 30 of a motor such as is used in a Ford automobile showing the improved gas saving device in association therewith.

Figure 2 is a top plan view of the transmission cover plate forming an important detail of the invention.

35 Figure 3 is a central longitudinal section taken approximately upon the line 3-3 of Figure 2.

Figure 4 is an enlarged detail view taken substantially upon the plane of the line 4-4 40 of Figure 1.

Referring to the drawings, it will be seen that the reference character 1 designates generally a motor of the type used in Ford automobiles, the same embodying the customary crank case 2, transmission housing 3, intake and exhaust manifolds 4 and 5 respectively, and an appropriate carburetor 6 connected with the intake manifold. Also connected with the carburetor and cooperating 45 with the exhaust manifold is a hot air conducting pipe 7 of conventional form, there being an appropriate valve 8 between the carburetor and pipe to control the intake of hot air derived from the exhaust manifold in the usual way. It is with this hot

air supply pipe 7 that the present improvement is immediately connected.

As before intimated, the invention comprises essentially a transmission cover 9 which, instead of being constructed as usual, is provided on its under side with a vapor collecting pocket 10. It will be noted that the pocket inclines downwardly toward its intake end so that condensed fuel vapors will be drained back into the transmission 65 casing. An opening 11 is formed at the discharge end of the pocket, and a pipe 12 is connected at its inner end to the cover plate so as to communicate with this opening. Detachably connected in any appropriate 70 manner with the free end of the pipe 12 and the intermediate portion of the hot air pipe 7 is a flexible tube 13.

From the foregoing it will be obvious that under the suction produced by the engine all 75 vapors and otherwise wasted gas will be collected upon the crank case and conducted through the pocket 10, pipe 12 and tube 13 into the carburetor to be mixed with the fuel mixture there ordinarily formed. By 80 associating the tube 13 with the pipe 7 it is obvious that the vapors passing through the tube will be pre-heated before entering the carburetor.

Actual use of a device constructed strictly 85 in accordance with the present invention has shown that it undoubtedly increases the efficiency of the motor. Not only does it save gasoline, but by relieving the crank case of the harmful, yet useful vapors, it constitutes 90 an oil purifying device, by preventing such vapors from divesting the oil of useful constituents. It has been observed too, that the motor runs smooth, that carbon deposits are reduced and that the oil in the crank case 95 is kept from freezing in cold weather. On the other hand, in warm weather it permits a circulation which serves to cool the oil and by relieving back pressure it in turn keeps the engine from pumping oil, whereby to 100 produce a more efficient lubrication of the valves, etc. By having the device attached to the rear of the crank case, or rather to the transmission casing, instead of to the breather pipe as is frequently done, it prevents the formation of a partial vacuum, thus giving the motor a place to admit air and still not hindering lubrication of the pistons and cylinder walls. These and other 105 advantages and features of the invention 110

have doubtless been made apparent by the foregoing description and drawing. For this reason a more lengthy description is thought unnecessary.

5 Although the preferred embodiment of the invention has been shown and described, it is to be understood that minor changes coming within the field of invention claimed may be resorted to if desired.

10 Having thus described the invention, what we claim as new is:—

In combination, a transmission cover hav-

ing its intermediate portion raised to form a pocket, a plate extending from the forward end of the pocket and inclining downwardly 15 and terminating below the lower end of the pocket, walls rising from the sides of the plate and fixed to the cover, a pipe extending from the upper end of the pocket in the cover.

20 In testimony whereof we affix our signatures.

JOHN MATTUS.
WALTER BETCKE.
